UNITED STATES PATENT OFFICE.

PERRY J. SNOWDEN, OF INDIANAPOLIS, INDIANA, ASSIGNOR, BY MESNE ASSIGNMENTS, TO E.-Z. OIL BURNER CORPORATION, OF INDIANAPOLIS, INDIANA, A CORPORATION OF INDIANA.

OIL BURNER FOR COOK STOVES AND THE LIKE.

Application filed August 7, 1924. Serial No. 730,696.

To all whom it may concern:

Be it known that I, PERRY J. SNOWDEN, a citizen of the United States, and a resident of Indianapolis, county of Marion, 5 and State of Indiana, have invented a certain new and useful Oil Burner for Cook Stoves and the like; and I do hereby declare that the following is a full, clear, and exact description thereof, reference being 10 had to the accompanying drawings, in which like numerals refer to like parts.

This invention relates to a fuel oil burner adapted to burn kerosene and the like.

The chief object of the invention is to construct 15 a burner of the character described which is suitable for stove use, particularly heating stoves and cook stoves, etc.

The chief feature of the invention consists 20 in the super-positioning of the several parts constituting the burner and the gravity flow of vapor produced in said burner into meeting engagement with the rising air currents supplied to the burner, which produces a peripherally surrounding frame 25 for heating purposes including vaporizing the fuel.

Another feature of the invention consists 30 in the provision of a plurality of superposed vaporizing chambers having restricted communication with each other and the lowermost chamber discharging laterally 35 the vaporized fuel from a well and beneath the chamber in immediate communication therewith.

Another feature of the invention consists 35 in the provision of an annular air supply which includes a plurality of covered tubular portions separated by intermediate portions, said tubular portions having a substantially free and laterally and inwardly discharging aperture and said connecting portions having a perforated cover 40 for discharging air upwardly and outwardly into meeting engagement with lateral 45 discharged fuel in vapor form which is discharged transversely of the first mentioned air supply.

The full nature of the invention will be understood from the accompanying drawings and the following description and claims:

In the drawings Fig. 1 is a top plan view of the invention. Fig. 2 is a transverse central sectional view taken on line 2—2 of

Fig. 1 and in the direction of the arrows. 55

In the drawings 11 indicates a peripherally and herein circular outlined base member including an inwardly extending flange 12. Projecting upwardly from said flange 12 is a peripherally outlined flange 13 60 which may or may not be similar to the outline of the portion 11. A central aperture 14 is provided and the wall 15 thereof constitutes a support ledge for the suitably outlined air supply member or secondary base. Said base includes an outer wall 16 and an inner wall 17. Connecting said walls are the radially positioned walls 18 arranged in spaced relation to form tubular portions indicated at 19, which discharge inwardly and laterally through openings 20.

The top 21 forms a supporting portion which, however, is separated from the adjacent supports and similar supporting portions by an air gap. This air gap is formed by the cover portion 23 having the air ports 22 therein which cover connection is adjacent radial walls 18. Air in the peripherally outlined channel formed by the outer and inner walls, 16 and 17 respectively, thus is discharged upwardly and outwardly from the perforated cover 23 and inwardly and laterally through the outlets 20 of the tubular constructions. 85

The inner wall 17 at its lower end is extended inwardly and upwardly and terminates in a central hollow support 24 connected to said wall by the intermediate portion 25. The central support 24 is adapted 90 to receive the tubular portion 26 which is externally threaded at 27 to receive a nut 28 for drawing together the remainder of the casing connected with said tubular portion 26 so that it rests as indicated at 29 95 upon the cover portions 21. Plate portion 30 forms a lower wall of the chamber through which the hollow stem 31 extends. The top of said chamber is formed by a separating plate or partition 32 integral 100 with said stem. Depending from said bottom plate 30 is a well 33 which includes a depending skirt portion 34 that encircles the tubular portion 26 adjacent the outlets 35.

The hollow stem 31 is threaded as at 36 and fuel is supplied to said tubular stem 31 through suitable means 10 having a thread-

ed engagement with said stem. The air which passes up between the walls of the hollow support 26 and the fuel supply line discharges laterally and outwardly through the ports 35 and is deflected downwardly by the skirt 34 before passing upwardly and outwardly into meeting engagement with the laterally and outwardly discharging fuel and the laterally and upwardly discharging flames.

Depending from the base 30 in the spaces formed by the radial walls 18 and connected by the cover 23 is a depending projection 37. It is to be noted from an examination of the Fig. 2 that air discharged through the ports 20 does not impinge upon the walls of the well 33 at that portion where the apertures 38 are provided. These apertures lie adjacent the skirt 37. It will thus be apparent that the air which is supplied through the ports 20 divides upon the inner wall of a channel defined by the well 33 and passes laterally along said wall and creates a suction upon the ports 38 for the drawing of vaporized fuel therethrough and into intimate mixture. This vaporized mixture is deflected upwardly and outwardly by air discharged by ports 35 and ports 22.

The stem 31 carries a fuel supplying and distributing spider 40. The ends of the spider arms discharge into a peripheral ring or fuel receiving groove 41. The fuel received thereby discharges over the edge thereof and impinges upon the upper face of the partition 32 and is deflected thereby toward the outer wall 42 which herein is shown inclined inwardly and downwardly. Immediately beneath the partition 32 and adjacent the downwardly extending edge 43 thereof is a nesting groove 44. Surrounding the well 33 is a rim or projection 45. The fuel discharged into the groove 44 forms a partial seal and excess liquid fuel discharges into the chamber therebeneath and is trapped by the rim 45 and retained until vaporized by the flames engaging that portion of the base 30 and the adjacent portion of the side wall 42. A curved or dome shaped cover 46 is suitably secured as by the bolt and nut construction 47 to the securing flange 48 formed integral with the inclined vaporizing wall 42 and on the upper edge thereof.

Also associated with the inclined wall and substantially surrounding the same is a plate portion 49 which is provided with a depending flange 50 that includes suitable extensions 51 which extensions are adapted to close the space formed between adjacent walls 18 connected by the apertured cover or top portions 23. The plate portion 49 is suitably apertured as at 52 and the purpose of this skirt or ring formed member is to distribute the flames formed at the junction of the three air currents and the fuel or vapor current and cause the same to encircle

the inclined wall 42 with substantial uniformity rather than in spotted or localized relation which would be the case were it not for the addition of this skirted construction 49-51 inclusive.

In communication with the channel 55 formed by the intermediate portion 25, the inner wall 17, and the bearing 24, is a discharge conduit or pipe 56 that projects beyond the wall 13 and is adapted to discharge excess fuel into the trough 57 formed by the three wall portions, 11, 12 and 13. This insures starting of the burner since when the fuel is supplied to the tubular stem or standard 31 it first discharges as liquid fuel through the ports 38 into chamber 55 and thence through the pipe 56 to the ring 57. Ignition of the fuel in this ring serves to heat not only the incoming air discharged through the tubes 19 but also serves to heat the inclined wall 42 of the interior construction and in this way initial vaporization of the fuel is secured. Thereafter the vaporization is automatic and continuous.

The invention claimed is:

1. In an oil burner, the combination of a plurality of peripherally arranged laterally and inwardly discharging air tubes, a plurality of upwardly discharging air outlets positioned between said air tubes for forming a combined air stream, and an upwardly directed air channel centrally positioned and including laterally and outwardly discharging air outlets communicating with the upwardly discharging air outlets.

2. In an oil burner, the combination of a plurality of peripherally arranged laterally and inwardly discharging air tubes, a plurality of upwardly discharging air outlets positioned between said air tubes for forming a combined air stream, and a superposed vaporizing chamber including a well provided with outwardly and laterally discharging fuel supply ports for discharging fuel into the inwardly discharged air current.

3. A device of the character described in claim 1 including a superposed vaporizing chamber having a well provided with outwardly and laterally discharging fuel ports for discharging fuel into the inwardly discharged air currents.

4. A device of the character described in claim 2 characterized by said vaporizing chamber having depending portions positioned in radially registration with the outwardly discharging fuel supply ports and positionable between said air tubes.

5. In an oil burner, the combination of a plurality of peripherally arranged laterally and inwardly discharging air tubes, a plurality of upwardly discharging air outlets positioned between said air tubes for

- forming a combined air stream, an upwardly directed air channel centrally positioned and including laterally and outwardly discharging air outlets communicating with the upwardly discharging air outlets, and a superposed vaporizing chamber including a well provided with outwardly and laterally discharging fuel supply ports for discharging fuel into the 5 inwardly discharged air current, a central air channel including laterally and outwardly discharge air outlets, both sets of said outlets being arranged for forming the combined air stream into which the fuel 10 is discharged and said vaporizing chamber having depending portions positioned in radial registration with the outwardly discharging fuel supply ports and positionable between said air tubes for forming a 15 baffle adjacent the fuel discharge.
6. In an oil burner the combination of a vaporizing chamber construction including outwardly discharging fuel supplying ports positioned near the bottom thereof, 20 air supplying means positioned in surrounding relationship with respect to said vaporizing construction and discharging air upwardly and outwardly, and a perforated skirt positioned between said vaporizing construction and said air supplying means, substantially as and for the purpose 25 described.
7. In an oil burner the combination of a plurality of peripherally arranged and spaced air supplying tubes, a vaporizing chamber positioned thereabove and extending downwardly within said peripherally arranged tubes and in spaced relation therewith, and a skirt construction substantially surrounding said vaporizing construction and having depending portions positioned between said tubes for substantially enclosing the depending vaporizing 30 construction.
- 45 8. In an oil burner the combination of a vaporizing construction including a depending well having outwardly discharging fuel supply ports, means for supplying air in surrounding relation with said well including air discharging means positioned beneath said well and discharging laterally and outwardly therefrom, other air discharging means positioned adjacent thereto for discharging upwardly and outwardly and transversely of the fuel discharge, other means discharging air inwardly and about said well, and a deflecting skirt positioned adjacent the outwardly discharging fuel ports.
- 50 9. In an oil burner the combination of a vaporizing construction including a depending well having outwardly discharging fuel supply ports, means for supplying air in surrounding relation with said well including air discharging means positioned beneath said well and discharging laterally and outwardly therefrom, other air discharging means positioned adjacent thereto for discharging upwardly and outwardly and transversely of the fuel discharge, other means discharging air inwardly and about said well, and a deflecting skirt positioned adjacent the outwardly discharging fuel ports.
- 55 10. In an oil burner the combination of a vaporizing construction including a depending well having outwardly discharging fuel supply ports, means for supplying air in surrounding relations with said well including air discharging means positioned beneath said well and discharging laterally and outwardly therefrom, other air discharging means positioned adjacent thereto for discharging upwardly and outwardly and transversely of the fuel discharge, other means discharging air inwardly and about said well, and a depending deflecting portion upon said well and positioned in the path of said outwardly and laterally discharging air supply means.

- 60 11. In an oil burner the combination of a vaporizing construction including a depending well having outwardly discharging fuel supply ports, means for supplying air in surrounding relation with said well including air discharging means positioned beneath said well and discharging laterally and outwardly therefrom, other air discharging means positioned adjacent thereto for discharging upwardly and outwardly and transversely of the fuel discharge, other means discharging air inwardly and about said well, and a depending deflecting portion upon said well and positioned in the path of said outwardly and laterally discharging air supply means.
- 65 12. In an oil burner the combination of a vaporizing construction including a depending well having outwardly discharging fuel supply ports, means for supplying air in surrounding relation with said well including air discharging means positioned beneath said well and discharging laterally and outwardly therefrom, other air discharging means positioned adjacent thereto for discharging upwardly and outwardly and transversely of the fuel discharge, other means discharging air inwardly and about said well, and a depending deflecting portion upon said well and positioned in the path of said outwardly and laterally discharging air supply means.
- 70 13. In an oil burner the combination of a vaporizing construction including a depending well having outwardly discharging fuel supply ports, means for supplying air in surrounding relation with said well including air discharging means positioned beneath said well and discharging laterally and outwardly therefrom, other air discharging means positioned adjacent thereto for discharging upwardly and outwardly and transversely of the fuel discharge, other means discharging air inwardly and about said well, and a depending deflecting portion upon said well and positioned in the path of said outwardly and laterally discharging air supply means.
- 75 14. In an oil burner the combination of a vaporizing construction including a depending well having outwardly discharging fuel supply ports, means for supplying air in surrounding relation with said well including air discharging means positioned beneath said well and discharging laterally and outwardly therefrom, other air discharging means positioned adjacent thereto for discharging upwardly and outwardly and transversely of the fuel discharge, other means discharging air inwardly and about said well, and a depending deflecting portion upon said well and positioned in the path of said outwardly and laterally discharging air supply means.
- 80 15. In an oil burner the combination of a vaporizing construction including a depending well having outwardly discharging fuel supply ports, means for supplying air in surrounding relation with said well including air discharging means positioned beneath said well and discharging laterally and outwardly therefrom, other air discharging means positioned adjacent thereto for discharging upwardly and outwardly and transversely of the fuel discharge, other means discharging air inwardly and about said well, and a depending deflecting portion upon said well and positioned in the path of said outwardly and laterally discharging air supply means.
- 85 16. In an oil burner the combination of a vaporizing construction including a depending well having outwardly discharging fuel supply ports, means for supplying air in surrounding relation with said well including air discharging means positioned beneath said well and discharging laterally and outwardly therefrom, other air discharging means positioned adjacent thereto for discharging upwardly and outwardly and transversely of the fuel discharge, other means discharging air inwardly and about said well, and a depending deflecting portion upon said well and positioned in the path of said outwardly and laterally discharging air supply means.
- 90 17. In an oil burner the combination of a vaporizing construction including a depending well having outwardly discharging fuel supply ports, means for supplying air in surrounding relation with said well including air discharging means positioned beneath said well and discharging laterally and outwardly therefrom, other air discharging means positioned adjacent thereto for discharging upwardly and outwardly and transversely of the fuel discharge, other means discharging air inwardly and about said well, and a depending deflecting portion upon said well and positioned in the path of said outwardly and laterally discharging air supply means.
- 95 18. In an oil burner the combination of a vaporizing construction including a depending well having outwardly discharging fuel supply ports, means for supplying air in surrounding relation with said well including air discharging means positioned beneath said well and discharging laterally and outwardly therefrom, other air discharging means positioned adjacent thereto for discharging upwardly and outwardly and transversely of the fuel discharge, other means discharging air inwardly and about said well, and a depending deflecting portion upon said well and positioned in the path of said outwardly and laterally discharging air supply means.

In witness whereof, I have hereunto affixed my signature.

PERRY J. SNOWDEN.
